Patented Mar. 26, 1918.

UNITED STATES PATENT OFFICE.

WILLIAM STEGER, OF LINDEN HEIGHTS, OHIO.

SCREEN.

1,260,589.

Specification of Letters Patent. Patented Mar. 26, 1918.

Application filed August 7, 1916. Serial No. 113,567.

To all whom it may concern:

Be it known that I, WILLIAM STEGER, a citizen of the United States, residing at Linden Heights, in the county of Franklin 5 and State of Ohio, have invented a new and useful Screen, of which the following is a specification.

This invention relates to metal screens, one of its objects being to provide a screen 10 in which the wire fabric can be renewed readily without requiring the services of a skilled mechanic.

A further object is to provide a screen frame, the stiles and rails of which are connected at the corners of the frame by an invisible connection.

Another object is to provide a screen, the parts of which can be assembled readily without requiring the services of an expert.

With the foregoing and other objects in view which will appear as the description proceeds, the invention resides in the combination and arrangement of parts and in the details of construction hereinafter described 25 and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—

Figure 1 is an elevation of a screen having the present improvements combined therewith.

Fig. 2 is an enlarged elevation of the outer side of one corner portion of the 40 screen.

Fig. 3 is a view similar to Fig. 2 but with the clamping strip and the fabric removed.

Fig. 4 is an enlarged section on line A—B Fig. 2.

Fig. 5 is a section on line C—D Fig. 2, the fabric being removed.

Fig. 6 is an enlarged section on line E—F Fig. 1.

Fig. 7 is an enlarged section through a 50 portion of one of the stiles of the screen frame, said section being on the line G—H Fig. 1.

Fig. 8 is a perspective view of one of the corner plates.

Referring to the figures by characters of reference 1 designates the stiles of a screen

frame and 2 and 3 designate the top and bottom rails respectively. Each of these stiles and rails is formed with mitered ends and each of them is formed of a channeled strip of sheet metal, the open faces of the strips being located at the outer side of the screen, while a longitudinal bead 4 is pressed inwardly along the inner side of each strip. One of the stiles may be provided with bow 65 springs 6 secured thereto and constituting means for engaging the window or door casing in which the screen is mounted.

Each of the stiles and rails has a flange 7 extending inwardly therefrom from the 70 inner edge of the outer side thereof, this flange merging into an inwardly extending obliquely disposed apron 8 projecting into the channel strip of which the rail or stile is formed. Another flange 9 is formed along 75 that side of the open face of the channel strip remote from the flange 7 and this flange is rounded as shown particularly in Fig. 4, its free edge lying close to the adjacent wall of the strip.

For the purpose of holding together the rails and stiles at their ends, corner plates 10 are employed. Each of these corner plates is substantially L-shaped and has a bead 11 rolled thereinto along the longitudinal center thereof, this bead being adapted to straddle the beads formed upon the meeting members of the screen. The plates 10 fit snugly within the meeting channel strips and have flanges 12 extending along the longitudinal edges thereof, the flanges along the outer edges of the plates being adapted to engage between the outer walls of the channel strips and the flanges 9, while the remaining flanges on the corner plates are 80 adapted to fit between the inner walls of the channel strips and the aprons 8. The plates can be assembled with the channel strips by slipping said corner plates longitudinally 85 into engagement with the end portions of the stiles and rails until the angle portions of the corner plates fit snugly within the meeting ends of the rails and stiles. After the parts have thus been assembled, an ordinary nail punch can be used for the purpose 95 of forming depressions, such as shown at 13, in the stiles and rails and within the corner plates. After these depressions have been struck into the parts, it will be obviously a difficult matter to pull the parts out of 100 engagement with each other.

For the purpose of securing a screen fab-

ric, such as shown at 14, to the screen, a series of holding strips are employed. Each of these strips has mitered ends and is formed of sheet metal, said strips being provided along their longitudinal edges, with substantially parallel inclined flanges 15 while the intermediate portion 16 of each strip is preferably formed with a longitudinal groove or depression 17. Flanges 15 are adapted to be received within the channeled stiles and rails and are so proportioned that when they are forced thereinto, one flange of each of the holding strips will bind against a portion of the screen fabric, while the opposed portion of each of the holding strips will yieldingly engage the flange 9. This flange, by reason of its peculiar rounded formation, not only serves as a spring for binding the inserted holding strip against the inserted portion of the wire fabric so as to clamp said fabric securely against the apron 8, but also acts as a lock to prevent accidental withdrawal of the holding strip from the channel strip. While one of the flanges 15 of each strip serves as a clamping member, the other flange 15 acts as a means for limiting the movement of the clamping strip inwardly into the stile or rail engaged thereby.

30 The holding strips are adapted to fit tightly together at their ends but one of them is preferably bent outwardly to a slight extent as shown at 18 so that a knife or other like device can be forced under said strip thus to enable the strip to be pressed out of the channel strip engaged thereby and to give access to the remaining holding strips which can likewise be removed.

35 The springs 6 broadly considered do not constitute any part of the present invention but have been fully disclosed in my Patent No. 1,010,700 issued to me on December 5, 1911, and I merely utilize the same as a means for holding the screen in its guides, it being possible by pulling laterally on the screen, to place the springs 6 under compression and disengage one stile from the guide of the window casing.

40 One of the means for fastening a spring 6 to the device has been illustrated in detail in Fig. 7. One end portion of the spring is engaged by one end of a holding strip 19 wrapped therearound and which strip bears against the outer side of the stile 1 and is bent inwardly so as to hook upon the inner edge of the flange 9, the hooked portion of the strip 19 being shown at 20. Thus when the holding strip 16 is pressed into position it will engage the inwardly extending portion of the hooked strip 19 as shown in Fig. 7.

45 Lifts 21 can be placed wherever desired upon the screen frame and in Fig. 1 two of these lifts have been shown upon the bottom portion of the frame. These lifts, which

50 are of any suitable form, are pivotally mounted in eyes 22 formed by the intermediate portions of a metal strip 23. This strip has two arms 24 and 25, the arm 24 extending across the inner face of the stile 70 and terminating in a lip 26 engaging the vertical face of the channel member 3, while the other arm 25 extends along the flange 7 and terminates in a hook 27 which engages the inner edge of the apron 8.

55 Should it be desired to arrange hinges upon the screen frame, one of which has been indicated at 28, the arrangement illustrated in Fig. 6 could be employed. As shown in this figure one of the leaves of the hinge 28 is provided with two arms 29 and 30, the arm 29 extending inwardly along the flange 9 and terminating in a hook 31 which engages the inner end of the flange. The other arm 30 extends along the free outer 85 faces of the stile and terminates in a lip 32 which engages the flange 7.

60 In all of the structures shown the parts employed for holding the springs, lifts and hinges can be readily slipped longitudinally 90 into position before the parts of the frame have been assembled and after they have thus been positioned, they can be secured by striking depressions in the metal with a nail punch or the like.

65 By providing the beads 4 which project into and fit snugly within the beads 11, a rigid joint is produced at each corner, the interfitting beads 4 and 11, the flanges 12 and the flanges 7 and 9 all coöperating to 10 produce a rigid frame. The depressions 13 serve to prevent the stiles and rails from slipping off of the corner plates.

70 While the frame herein described is especially designed for use in connection with wire fabric, it is to be understood that the same can also be used for holding any other kind of fabric, such as canvas or the like.

75 What is claimed is:—

1. A window screen including a frame made up of abutting mitered channel strips, each strip having an inwardly directed obliquely disposed apron along its inner side and an inwardly projecting longitudinally extending locking flange along its outer side, a fabric having its edge portions insertible between the flanges in said channel strips, and a clamping strip insertible into the channel strips and having meeting mitered ends, each clamping strip including a flange 1 coöperating with the apron to bind upon a portion of the screen fabric, and a flange for limiting the movement of the clamping strip into the channel strip.
2. A screen including a frame made up of mitered meeting channel strips, each strip having one face open and provided along one side with an inwardly extending obliquely disposed apron and along its other side with an inwardly extending locking

- flange, means fitted within the end portions of the channel strips for securing them together, a screen fabric having its edge portions extending into the channel strips, and holding strips insertible into the open faces of the channel strips, said holding strips having obliquely disposed flanges coöperating with the apron to bind upon the inserted portions of the screen fabric and having means for limiting the inward movement of the holding strips relative to the channel strips, said locking flanges coöperating with the apron to secure the holding strips within the channel strips.
- 15 3. A screen including a frame made up of mitered meeting channel strips, each strip having one face open and provided along one side with an inwardly extending obliquely disposed apron and along its other side with an inwardly extending locking flange, means fitted within the end portions
- of the channel strips for securing them together, a screen fabric having its edge portions extending into the channel strips, and holding strips insertible into the open faces 25 of the channel strips, said holding strips having obliquely disposed flanges coöperating with the apron to bind upon the inserted portions of the screen fabric and having means for limiting the inward movement 30 of the holding strips relative to the channel strips, said locking flanges coöperating with the apron to secure the holding strips within the channel strips, one of said holding strips having an offset end portion. 35
- In testimony that I claim the foregoing as my own, I have hereto affixed my signature in the presence of two witnesses.

WILLIAM STEGER.
